LEO K. STAFFORD, OF NEW YORK, N. Y.

JOURNAL BOX AND MOUNTING.

1,406,099.

Specification of Letters Patent. Patented Feb. 7, 1922.

Original application filed April 27, 1920, Serial No. 376,971. Patent No. 1,370,377, dated March 1, 1921. Divided and this application filed December 14, 1920, Serial No. 430,680.

To all whom it may concern:

Be it known that I, LEO K. STAFFORD, a citizen of the United States, residing at New York, in the county of Bronx and State of New York, have invented new and useful Improvements in Journal Boxes and Mountings, of which the following is a specification.

My present invention has reference to a journal box for the axles of the wheels of railway rolling stock, and a mounting for said box, and is a division of the application filed by me April 27, 1920, Serial No. 376,971.

The improvement is primarily devised for use in connection with anti-frictional bearing means between a car wheel journal and the journal box therefor. In such constructions, it is absolutely necessary that the bearings, and consequently the box carrying the bearings, be at all times retained in longitudinal alignment with the journal. Otherwise the bearings would create friction between the journals and the boxes which would render the bearings defective, subject the same to breakage, and cause injury to be inflicted to both the journal and to the box. As is well-known in railway constructions, it is frequent that the rail on one side of a track is disposed at a greater or less elevation than the rail on the other side of the track, and as the wheels of the rolling stock must at all times follow the rails the truck frame or mounting for the journal box must necessarily be of a character which will yield laterally on the box to compensate for such irregularities in the rails of the track and not influence the journal box, with respect to its longitudinal alignment on the axle, to prevent unnecessary friction between the roller bearings, the journal and the box, or damage which would otherwise be inflicted to such parts.

It is therefore to be considered the primary object of the present invention to produce a journal box which carries anti-frictional rollers that engage with the journal or spindle of the axis for the wheels of rolling stock, and a mounting therefor which is susceptible to lateral angular movements on the box without affecting the longitudinal alignment of the box on the journal.

It is a still further object of the invention to produce a journal box for the journals

on the wheels of railway rolling stock and a mounting therefor, in which fulcrum means is provided between the mounting and the box which will permit the mounting to assume angular positions with respect to the box, when the wheels of the rolling stock pass over irregular track surfaces, and wherein the degree of the angle assumed by the mounting will be limited by means between the mounting and the box.

It is a still further object to produce a journal box which carries anti-frictional bearings to engage with the journal on the wheel of a railway rolling stock, wherein a fulcrum engagement between the top of the box and the top of the mounting is produced, and wherein the means that secure the box to the mounting serve to limit the angular positions which the mounting may assume with respect to the box.

The foregoing, and other objects which will appear as the nature of the invention is better understood, may be accomplished by a construction, combination and operative association of parts, such as is disclosed by the drawings which accompany and which form part of this application.

In the drawings:

Figure 1 is a side elevation of the improvement, parts being broken away and parts being in section.

Figure 2 is a side elevation illustrating a slight modification.

Figure 3 is a front elevation of the box shown in Figure 1, with parts broken away and parts in section.

Figure 4 is an elevation looking toward the front of a journal box of a slightly modified construction, showing the same positioned on a mounting such as is commonly employed for supporting the journals of the wheels for passenger coaches.

Figure 5 is a sectional view approximately on the line 5-5 of Figure 4.

Figure 6 is a sectional view approximately on the line 6-6 of Figure 5.

From experience, I have found that the great deficiency in attempts heretofore made for providing anti-frictional bearings between the journals for the wheels of railway stock resides in the fact that due consideration has not been given to the absolute necessity of the provision of means between the journal box carrying the anti-frictional

bearings and the mounting of said box on the truck in a manner which will permit of a limiting rocking or lateral angular positions of the mounting on the truck when 5 irregularities with respect to the height of the rails on the track are encountered. All such devices which have come under my observation have been worked out in accordance with the theory as applied to the 10 anti-frictional bearings between the spindle of a shaft and the ordinary vehicle wheel, in which spring supports are provided between the axles and the body of the vehicle. In railway rolling stock, the journal or 15 spindle of the axle is projected beyond the face of the wheel, and the truck frame or bearing support for the journal boxes and for the body of the rolling stock, while yieldable with respect to the said body, are 20 not susceptible to a slight swinging or lateral movement on the boxes. Consequently, the longitudinal alignment of the roller bearings in the boxes and the journals with which the same engage are materially 25 interfered with, creating friction and damage to parts, and rendering the roller bearings not only defective but absolutely inoperative so that the same are positively impractical and detrimental in the use for 30 which they are designed.

As the description progresses, it will be readily seen by those having knowledge of the art to which this invention relates that I have successfully overcome the deficiencies 35 above referred to, and that also I have provided means whereby friction between the journal and the journal box of railway stock is reduced to such an extent that the car or coach may carry a far greater weight without liability of damage to the wheels, journals, journal boxes and supports therefor, than has heretofore been accomplished.

Referring now to the drawings in detail, the numeral 1 designates the journal or spindle end of an ordinary axle for the wheels 45 of railway rolling stock. The journal 1, of course, projects beyond the outer face of the wheel (not shown), and has its spindle end received in a journal box 2.

50 By reference to Figure 3 of the drawings, it will be seen that anti-frictional rollers 4 are disposed in circular series between a bushing 5 that is swaged on the journal spindle 6, and a bushing 7 that is swaged 55 to the inner face of the journal box. Of course, other arrangements of anti-frictional bearings may be provided between the box and spindle.

The box, in the showing in Figures 1 and 60 3 of the drawings is designed for use on freight carrying cars. The box 2, at its top, and at the center thereof has a lateral projection in the nature of a lug 8, and this lug has its corners rounded toward the box, 65 as at 8'. The box 2, on the sides thereof,

and at its top and bottom portions is provided with outstanding ears 9 and 10 respectively, and each of the said ears has an elongated opening 11 therethrough. The sides of the box, between the ears 9 and 10 70 are formed with ribs 12 respectively. These ribs, from the central portion 13 thereof are inclined outwardly, providing angle walls or shoulders 14 which terminate in the end walls provided by the outstanding ears 10. 75 Thus the central portions of the confronting faces of the ribs 12 are pointed.

The mounting for the box is in the nature of the usual frame. In this connection, it is thought desirable to state that except for 80 the journal box, no changes are made in the car construction. The upper bar 15 of the mounting rests directly on the lug 8, while the lower bar 16 of the mounting is disposed a slight, but sufficient distance from 85 the bottom of the box to permit of a lateral swinging motion or yielding of the mounting on the box without permitting the lower bar 16 being brought into contact with the box, or otherwise interfering with such 90 movement of the mounting.

Passing through the upper and lower bars of the mounting, are bolts 17. The respective pairs of bolts pass through the elongated openings 11 in the ears 9 and 10 and 95 are received in the channel provided between the ribs 12. On the bolts, and having their ends contacting with the bars 15 and 16 respectively of the mounting, are sleeves 18 respectively, the said sleeves contacting 100 or being only slightly spaced away from the central pointed portions 13 of the angle ribs 12. The bolts 17 are engaged by nuts 19.

The upper bar of the mounting has a fulcrum engagement with the top of the journal box, incident to the engagement of the said bar with the lug 8. The means which secures the box to the mounting, that is, of course, the bolts and the sleeves thereon, being arranged in the channels between the 110 ribs 12, have a fulcrum engagement with the points 13 of the said ribs. Thus the mounting may rock or yield laterally with respect to the journal box, and such rocking or yielding will be limited by the contacting engagement of the sleeves 18 with the angle walls 14 of the ribs 12. When the mounting is at its extreme angular positions on the journal box, one side of each of the sleeves 18 will be in contact with either the upper or lower angle surface on one of the ribs 12, and the opposite side of the said sleeves will be in contact with the diagonal opposite angle surface on the other rib 12. Thus when in such position, both sides of the sleeves are 115 engaged by the ribs, but at opposite points. The sleeves relieve the bolts from undue strain.

In Figure 2 of the drawings, the journal 1' is received in a journal box 2' of a slightly 120

different construction from that above described. The journal box 2' has its sides provided with spaced ribs 12' arranged in opposed pairs. The ribs have their central portions thickened upon their inner confronting faces and are beveled or arranged at opposite outward inclinations from the central portions 13' thus provided, the angle walls to the opposite sides of the central points 13' being indicated by the numeral 14'. The top of the box, between the spaced pairs of ears is provided with a projection in the nature of a lug 8'', which is rounded from its center to its edges. The mounting 15 for the box has its ends provided with yokes, whose depending parallel arms 18' are received between the spaced pairs of ribs 12', the upper element 15' of the yoke resting on the lug 8'', and the lower ends of the yoke, 20 which project a suitable distance below the journal box 2' being connected by a plate 16'. With this construction, the ears 9 and 10 are dispensed with, as are also the anti-frictional rollers which surround the bolts 25 that connect the plates 15 and 16 in the mounting previously described.

In the remaining figures of the drawings, the journal box 20 has its sides provided with the spaced pairs of ribs 21, whose inner faces are disposed at opposite angles from the central point 22 therefor. The ribs 21 are spaced a further distance apart than are the ribs 12, for the reason that the ribs 21 receive therebetween the flat side members 30 23 of the yoke 24 that is employed in the usual construction of truck frames on passenger coaches. The top of the box 20 has a transverse cross sectionally rounded lug 24 thereon, and the said top, at the sides of the 35 lug are provided with upstanding flanges 25. Between these flanges, and resting on the fulcrumed lug 24, is the end of the equalizing bar 26 of the mounting construction. The lower bar 27 of the mounting is secured, 40 in the usual manner to the ends of the yoke 24, and is spaced from the bottom of the journal box 20, as clearly disclosed by the drawings, so that a rocking or lateral movement of the mounting on the box will not be 45 interfered with.

In both forms of my improvement, it will be noted, ample provision is made for positively retaining the anti-frictional roller bearings carried by the journal boxes in 50 proper and positive engagement with the spindles or journals of the wheel carrying axles, as well as the positive longitudinal or parallel arrangement of the box with respect to both the journal spindle and the 55 roller bearings. With my improvement, the wheels of the rolling stock will, at all times, and under all conditions follow the rails of the track, and as a consequence, the deficiencies above recited are not only effectively 60 overcome but the danger of derailment 65

which is always occasioned by the tread portions of the wheels of the rolling stock not positively engaging the heads of the rails, is also effectively overcome.

While I have illustrated and described a 70 satisfactory embodiment of the improvement as it now appears to me, it is to be understood that such departures may be made therefrom as fall within the scope of what is claimed.

Having described the invention, I claim:—

1. In combination, a journal box and a mounting therefor, means on the journal box engaging the mounting, and providing a fulcrum therebetween, means passing 80 through the mounting and contacting the sides of the box for connecting the box to the mounting, and means on the sides of the box at the opposite sides of the connecting means for engaging the latter for limiting 85 the rocking movement of the mounting on the box.

2. In combination, a journal box and a mounting therefor, fulcrum means between the upper surface of the journal box and the 90 mounting, means passing through the mounting contacting the sides of the box for securing the latter to the former, and angle ribs on the sides of the box opposite the connecting means for contacting engagement with 95 the latter and for limiting a rocking movement of the mounting on the box.

3. In combination, a journal box and a mounting, therefor, a transverse lug on the top of the box contacting the upper portion 100 of the mounting and providing a fulcrum therebetween, and the lower member of the mounting being out of contacting engagement with the lower face of the box, means passing through the members constituting 105 the mounting and contacting with the sides of the box for securing the latter on the former, said box having its sides provided with a passage for the reception of said securing means, and the walls of said passage 110 being disposed at an outward angle from the center thereof, as and for the purpose set forth.

4. In combination, a journal box and a mounting therefor, the latter including 115 members which are arranged over and below the box, a transverse rounded lug on the top of the box contacting the upper member of the mounting and providing a fulcrum therebetween, ribs arranged in spaced pairs 120 on the sides of the box, and having their confronting faces inclined outwardly from the center thereof, connecting means passing through the upper and lower members of the mounting and received between the ribs, and 125 said connecting means being in contact with the pointed centre of the ribs, as and for the purpose set forth.

5. In a means for holding anti-frictional 130 bearings in positive engagement between the

journal for the wheel of a railway car, and a journal box therefor, in combination with the journal box and a mounting for the box, of means carried by the box providing a fulcrum between said box and mounting, means carried by the mounting securing the journal box thereon, and means carried by the jour-

nal box disposed opposite the connecting means for engaging the latter when the mounting is subjected to a lateral rocking movement on the box.

In testimony whereof I affix my signature.

LEO K. STAFFORD.
